M. G. BROWN.

ATTACHMENT FOR FILLING GREASE CUPS.

APPLICATION FILED JUNE 14, 1910.

1,027,588.

Patented May 28, 1912.

UNITED STATES PATENT OFFICE.

MATTHIAS GEORGE BROWN, OF GULFPORT, MISSISSIPPI.

ATTACHMENT FOR FILLING GREASE-CUPS.

1,027,588.

Specification of Letters Patent.

Patented May 28, 1912.

Application filed June 14, 1910. Serial No. 566,872.

To all whom it may concern:

Be it known that I, MATTHIAS GEORGE BROWN, a citizen of the United States, residing at Gulfport, in the county of Harrison 5 and State of Mississippi, have invented certain new and useful Improvements in Attachments for Filling Grease-Cups, of which the following is a specification, reference being had therein to the accompanying drawing.

The invention comprehends a portable receptacle adapted to carry a quantity or supply of lubricant provided with means for removably attaching the same to a grease 15 cup and instrumentalities for discharging the desired amount of the lubricant from said receptacle into the cup.

As will appear to those skilled in the art, the invention also embraces the formation of a filling device of the general character referred to with a coupling element adapted to coöperate with a complementary element formed on a part of the grease cup structure facilitating a quick connection or disconnection 25 of the filling device relative to the said cup.

A convenient embodiment of the invention includes a grease cup formed with a seat communicating with a fill opening, a filling 30 device having a part to correspond with said seat and register with said fill opening, and a separable coupling intermediate of the filling device and the cup to temporarily retain the parts in proper coöperative association.

Preferably, also, the above stated embodiment of the invention comprises for the coupling means coöoperating separated flanges or lugs having opposing inclined faces to create a binding action therebetween 40 upon a relative turning of the parts, the arrangement being such that what I may term a "quick" engagement or release is afforded involving simply a quarter-turn of the one member relative to the other.

The foregoing characteristics of the invention, and the details in the construction and arrangement of the parts will be apparent from the specific description hereinafter contained when read in connection with the accompanying drawings forming part hereof and wherein the convenient embodiment of 50 the invention to which I have above alluded is illustrated.

In the drawings, Figure 1 is an elevation 55 of one end of a machine element, for instance, an engine pitman, having the usual

grease cup provided with my present improvements and the filling device attached thereto, Fig. 2 is an elevation of the filling device detached, Fig. 3 is a vertical longitudinal section through Fig. 1, Figs. 4, 5, and 6 are detail views showing the coupling devices.

Referring more specifically to the drawings, wherein like reference characters designate corresponding parts in the several views, A represents one end of an ordinary pitman, B the pin upon which the same is pivoted and which latter it is desirable to maintain in a lubricated condition, and C is the usual grease cup formed integral with the pitman opening through an aperture c 60 in the base thereof to the pivot pin B.

D is the cover for the oil cup having an internal threaded engagement d with the mouth of the cup and a wrench-hold d' as usual. As distinguished from the cap or cover customarily employed, the cover D in this instance is provided with an upwardly projecting centrally disposed stem d'' having 70 an aperture e communicating with the hollow interior d' of the cover C and arranged at the base of an inwardly tapering seat E at the mouth of said stem. At the upper end of the stem d'' and formed integrally therewith, a pair of separated lugs or flanges f are arranged to project laterally from the stem and overhang the top F of the cap D with spaces f' therebetween, said lugs or flanges being beveled or inclined on their under surfaces, and the separation thereof being for the purpose of providing what I may term entrance passages f'' for similar lugs or flanges on the lubricant receptacle 80 now to be described.

As will be apparent, the lubricant receptacle, represented at G may be of any desired size and shape, and the same may be provided with any preferred or suitable discharging means, that shown consisting of a hollow plunger or piston H having a threaded engagement g with the top of the receptacle, the upper end of the piston or plunger h being of angular formation to facilitate the adjustment thereof. The interior of the lower portion of the receptacle inclines to a discharge outlet i in the base I of the receptacle, a tapered nipple J being provided at this point to fit the seat E in the cap of the grease cup heretofore referred 90 to.

K are flanges spaced apart as at k, and

adjoining the base of the receptacle projecting inwardly from the lower edge of a tubular extension k' , of the receptacle G , extending a suitable distance below the nipple J to provide a space k'' therebetween. These flanges are also tapered, providing beveled or inclined upper surfaces and are adapted to be slipped through the entering openings on the cap and by approximately

10. a quarter-turn of the receptacle brought into impingement with the correspondingly tapered lugs or flanges f on the cap to create a wedging action between the lugs and a binding engagement between the nipple J 15 and its seat E . An angular surface g' on the receptacle facilitates the turning of the same to attach or detach the receptacle from the cap.

From the foregoing disclosure, it will 20 be appreciated that by the use of a construction in keeping with my invention, grease cups may be filled in an expeditious and cleanly manner, it being simply necessary to couple the attachment constituting the 25 grease gun or dispensing vessel to the cup as pointed out, and to manipulate the plunger or piston to effect the desired discharge of the lubricant from the receptacle into the cup, when the attachment may be 30 removed at will.

While I have herein disclosed but one specific embodiment of the invention, it is to be understood that the invention is capable of embodiment in other forms and 35 devices. For example, as I have hereinbefore noted the particular shape of the lubricant receptacle may be varied; the character

and arrangement of the expelling plunger may be changed, for instance, to provide an externally arranged hollow cap engaging 40 the receptacle; and the coöperating beveled lug-coupling idea may be the reverse from that shown, that is with the cap of the lubricant cup formed hollow with the internal lugs and the supply receptacle formed 45 with the external lugs.

I claim:

In a lubricating apparatus, the combination of a lubricant-receiving member mounted in fixed position on the article to be 50 lubricated, a cover for said member detachably connected to and carried by the mouth thereof having a relatively small aperture therethrough and a coupling member formed integrally therewith, a removable 55 lubricant-delivery member arranged in abutting relation to the lubricant-receiving member also having a relatively small aperture registering with the aperture in the cover and a complementary coupling member integral therewith coöperating with the coupling member on the cover to bind the two members together, and a tapered nipple and seat engagement between the two members surrounding the apertures thereof to 60 seal the joint therebetween when the coupling members are engaged.

In testimony whereof I affix my signature in presence of two witnesses.

MATTHIAS GEORGE BROWN.
